UNITED STATES PATENT OFFICE.

PETER B. BASTARACHE, OF BEVERLY, MASSACHUSETTS.

RIM TOOL.

Application filed November 12, 1921. Serial No. 514,542.

To all whom it may concern:

Be it known that I, PETER B. BASTARACHE, a citizen of the United States, residing at Beverly, in the county of Essex and Commonwealth of Massachusetts, have invented certain new and useful Improvements in Rim Tools, of which the following is such a full, clear, and exact description as will enable others versed in the art to which it 5 appertains to make and use the same.

My invention relates to tools or equipment for the better, easier, and more efficient handling, contracting, and expanding of so called demountable rims during the 10 process of mounting and demounting thereon the shoe portions of pneumatic tires.

The objects of my invention are:

To provide novel and improved means 15 of mounting and demounting pneumatic tires upon so called demountable rims of the type having two abutting ends.

To provide a new and improved quick gripping method for use in contracting said rims.

20 To provide a new and improved means of adjustment, making my device efficiently applicable for use on rims of considerably varying sizes.

To increase the efficiency of mounting and 25 demounting devices by direct application of force between opposite sides of said rim, at multiple points, eliminating so called hub or center portions and their incidental troubles.

30 To eliminate center binding and bulging of said mounting and demounting devices.

To provide a novel construction and arrangement of parts herein fully described and indicated in my appended claims.

40 I accomplish the objects of my invention as shown in the accompanying drawings in which Figure 1 is a side view of my mounting and demounting device in working position within an ordinary demountable rim.

45 Figure 2 is a sectional view on the line 4-4 in Figure 1. Figure 3 shows the detail of my rim engaging unit.

50 Referring to the drawing, 5 shows the demountable rim within which my device is positioned. The diametrical force applying means comprising two arms 6, arranged at right-angles to each other and joined at 7 adjacent their inner ends by the connecting screw 8, and each having at one end a rim 55 engaging unit 9 and at its other end having a screw-threaded stem 12², another rim en-

gaging unit 9 having a screw-threaded stem 13², and a solid turn-buckle 11 connecting the two stems 12² and 13². The diametrical arms 6 are provided with auxiliary threaded orifices 10 in which the connecting screw 8 interchangeably fits when it is desired to utilize my device on a different sized rim than here shown.

The turn buckle 11 is constructed with a 65 right and left thread, 12 and 13 respectively, within opposite ends of said turn buckle 11, which threads fit and operate on the stems, 12² and 13². The arms 6 are slightly bent at their center portion so as 70 to allow clearance for each other in use.

In Figure 3, 14 shows the flat portion of the rim-engaging unit which engages and rests against the inner surface of a demountable rim when my device is used in expanding said rim. 15 shows the hook formed to engage a demountable rim when my device is used in contracting said rim, as in removing a tire shoe therefrom. The tire gripping units are best positioned on opposite ends of the diametral arms 6 so as 80 to grip, one on the right and one on the left of the demountable rim.

Those familiar with the art will understand that my device is operated, expanded, 85 or contracted at will by turning the buckle 11, the right and left threads of which expand or contract the arms 6 longitudinally.

When intended for use within a rim smaller than shown in the drawing the connecting screw 8 is removed and the arms 6 reunited at the threaded orifices 10 into which the connecting screw 8 interchangeably fits.

The use of the improved turn buckle 11 95 adds much rigidity to the diametrical arms 6 by increasing the area of the inner supporting surface which bears on the threads 12² and 13². This construction avoids much of the loose play incidental to open center 100 turn buckles, and resulting reduces the tendency of my device to double up or buckle when force is applied in expanding the rims, within which the device is used. The elimination of all working parts at 105 the hub portion is also a major factor in this result. When the tool is in position within a rim, the arms 6 on the opposite side of the screw 8 from the stems 12², together with the portion of the rim extending between the outer ends of said arms, form a 110 substantially rigid triangular frame which

is not affected by the operation of the adjusting means, and each adjusting means is operable separate from the other, etc.

I do not desire to confine myself to the herein specifically defined construction, as future practice may require such changes as may well fall within the scope of my invention as defined in my appended claims.

Having thus described my invention I claim as new and desire to secure by Letters Patent of the United States of America—

1. A rim tool for expanding and contracting wheel-rims, comprising a pair of rigid arms having rim engaging hooks at their outer ends and joined together adjacent their inner ends and arranged substantially at right-angles to each other, and each arm being also provided with a threaded stem projecting in alined extension with its respective arm, and a rim-end adjusting means mounted on each of said stems and having a rim-engaging hook at the outer ends thereof.

2. A rim tool for expanding and contracting wheel-rims, comprising a pair of arms having rim engaging hooks at their

outer ends and joined together adjacent their inner ends and arranged substantially at right-angles to each other, and each arm being also provided with a threaded stem projecting in alined extension with its respective arm, and a rim-end adjusting means on each of said stems and embodying a turn-buckle, a second threaded stem having a rim-engaging hook on its outer end.

3. A rim-tool for expanding and contracting wheel-rims, comprising a pair of rigid arms having rim-engaging hooks at their outer ends, and provided with a series of apertures adjacent their inner ends, and a bolt joining said arms together and adapted to be interchangeably engaged in said apertures to vary the span of the tool, said arms being arranged substantially at right-angles to each other and also provided with threaded stems, and adjusting means on said stems having hooks to engage the rim.

In testimony whereof I affix my signature in the presence of two witnesses.

PETER B. BASTARACHE.
